ELECTRIC DRILL.

936,870.

Specification of Letters Patent. Patented Oct. 12, 1909.

Application filed May 3, 1905. Serial No. 258,675.

To all whom it may concern:

Be it known that we, WILLIAM O. DUNTLEY, a citizen of the United States, residing at Chicago, Cook county, Illinois, and 5 HENRY J. KIMMAN, a citizen of the United States, residing at Cleveland, Cuyahoga county, Ohio, have invented certain new and useful Improvements in Electric Drills, of which the following is a specification.

10 Our invention relates to portable tools such as drills, in which the motive power is electricity and the object of our invention is to produce an efficient and reliable tool or drill of this character, chief among whose 15 advantageous features is a provision for preventing overloading of the drill, the result being accomplished, in the present instance, by so constructing and arranging the driving connection between the motor and the 20 tool spindle that such connection is rendered inoperative when the drill becomes overloaded, with the result that the drill is stopped without interfering with or stopping the electric motor, which continues to 25 run without effect upon the tool spindle or drill.

Our invention relates to other advantageous features, such as a novel and original construction of switch device for the motor 30 circuit, as well as a novel and original form of force feed device for the tool or machine.

In the drawings, Figure 1 is a longitudinal sectional elevation of an electric drill embodying our invention; Fig. 2 a plan view 35 thereof; Figs. 3 and 4 details of the switch; Fig. 5 an elevation of the brush holder, and Figs. 6 and 7 sectional views illustrating modified forms of gearing.

Referring to the particular embodiment of 40 our invention as herein illustrated, the electric drill comprises a main casing 1, within which is arranged an electric motor 2, the casing preferably forming the field frame of such motor. Moreover, by preference, the 45 casing is provided with a series of flanges or ribs 3, for the purpose of radiating the heat that may possibly be generated and to assist the fan device in cooling the motor, as hereinafter described. By preference, the upper 50 portion of the casing is substantially cylindrical, but is outwardly flared at its lower end and provided at its extreme end with a flange 4, in order that the gear casing 5 may

be secured to the main casing of the machine or drill. Between this main casing and the 55 gear casing is clamped a lower head or diaphragm 6, in which is arranged the lower bearing 7 of the armature shaft 8 of the electric motor, which bearing may be of suitable construction, but herein shown as a ball 60 bearing. Another head 9 is arranged at the upper end of the main casing of the machine and the same is in the present instance and by preference, cast or formed integral with the main casing. This upper head is provided 65 with a suitable bearing 10, in the present instance a ball bearing, for the purpose of journaling the upper end of the armature shaft. The lower end of the armature shaft extends through its bearing and through the 70 diaphragm or lower head 6 and is formed as or provided with a pinion 11, which is arranged to mesh with a train of gears, for the purpose of transmitting the motion or rotations of the armature to the tool socket 75 or spindle 12, which receives the shank of the drill or other working tool in the well known manner. In the present instance, the particular form of gearing employed and herein illustrated is of the planetary type 80 comprising essentially two gears or pinions 13 revolving in connection with a circular rack 14 arranged in a socket in the upper end of the gear casing. These revolving gears are mounted to rotate freely on the 85 vertical studs 15, which are in turn secured upon the revolving yoke or gear frame 16 pinned or otherwise secured to the tool spindle 12. In the present instance, this tool spindle is provided with a tool socket 17 having a Morse taper. As illustrated in Fig. 1 the revolving gears proper do not mesh with the circular rack 14, but the same are provided with hubs 18 formed as pinions for directly engaging with the circular rack 14. 90

It will be understood that if the machine or drill should be constructed as just described, the same is liable to be overloaded from several causes, such as the use of a drill larger than the capacity or power of the machine, or by too great pressure or feed exerted on the tool or drill, with the result that owing to the consequent stoppage or slowing down of the electric motor, the latter would be supplied with such an amount of 105 current as would be liable to destroy or burn

out the armature windings. To overcome this objection of overloading, preferably without interfering with the motor or its current, is the principal feature of our present invention and to accomplish this result, we provide means whereby the gearing becomes inoperative when the load on the working tool reaches or exceeds a predetermined amount. In the present instance, this result is brought about through the medium of the circular rack 14, which is normally in a fixed or stationary position so long as the predetermined load is not reached or exceeded, but which is adapted to slip within its socket in the casing, whenever such predetermined load is reached or exceeded. In the normal operation the circular rack is in fixed position, as stated, and the revolving gears 13 are consequently enabled to transmit the motion of the motor to the tool spindle, but obviously when the predetermined amount of load is reached or exceeded and increased pressure brought to bear by the revolving gears or pinions against the rack the latter will slip and be rotated, with the result that the tool spindle will stop, while the electric motor will continue to run. In the present instance, the driving connection between the tool spindle and the motor may be considered a frictional drive in connection with gearing, the arrangement being such as hereinafter described, that the amount of friction or frictional resistance may be adjusted in degree at the will of the operator, so that the predetermined amount of load may be varied as described.

Referring to the construction as herein illustrated, the circular rack 14 co-operates with means for applying pressure or frictional resistance thereto, such means comprising a pressure applying ring 19, arranged below the circular rack and held theretoward with yielding pressure by means of a series of spring pressed studs 20. Each of these studs projects upwardly through the upper end of a spring case 21 formed on the gear casing and containing a spring 22 pressing against the head of the stud 20 and also against a nut 23 arranged to screw upon the spring case for the purpose of varying or adjusting the tension of the spring and consequently varying or adjusting the amount of the frictional resistance of the curved rack 14. In order to receive the upward thrust on the circular rack we provide an abutment 24, which is in the form of a ring secured to the gear casing. By preference, we provide between the rack 14 and the two rings 19 and 24, resistance rings 25 of suitable material such as fiber. We prefer to employ these fiber rings, inasmuch as the same provide a proper and uniform amount of resistance, and moreover cannot be crushed or become cut. The load which can safely be

carried by the machine or drill without injury to the motor can be easily determined and the adjusting nuts 23 can be adjusted to the proper position to provide that amount of frictional resistance to the rack 14 corresponding with such predetermined load. When such load is reached or exceeded the rack will slip or rotate in the manner hereinbefore described without endangering the electric motor. It will be understood that when the load exceeds the predetermined amount and the tool spindle stops or runs slowly, the electric motor will not race or run wild, inasmuch as the predetermined amount of load is still carried by it, because of the fact that it is at such time, rotating the rack on which the frictional resistance is constant. Consequently, the motor carries the predetermined amount of load, but is relieved of the excess load.

We do not limit our invention to the specific character of gearing illustrated in Fig. 1, nor to the specific manner or means for obtaining the results hereinbefore referred to, inasmuch as the same results could be accomplished by other specific means without departing from the spirit of our invention, and furthermore, our invention is applicable in respect to other constructions of gearing, as illustrated in Figs. 6 and 7 hereinafter described.

Referring next to the switch device, as illustrated in general in Fig. 1 and in detail in Figs. 3 and 4, the same comprises two spring terminals 26 arranged in the motor circuit and supported by the insulating block 27, fastened, in the present instance, on the upper surface of the lower head or diaphragm 6. The connection between these terminals is under the control of two keys or buttons 28 and 29, which are arranged to project from the upper surface of an extension 30 of the main casing and on either side of one of the grasping handles 31, which, as indicated in Fig. 1, is secured into one side of the main casing. The lower end of the button 29 is provided with means for electrically connecting the two terminals and, in the present instance, such means consists of an anti-friction roller 32 of conducting material, with the result that when the button 28 is in its innermost position, as illustrated in Fig. 4, the motor circuit is closed, the other button 29 being at this time in its outermost position. For the purpose of holding the buttons with a yielding pressure in one position or the other, we provide suitable means such as the lever 33, rocking on the axis 34 intermediate its length with its ends bearing in and engaging the side recesses 35 and 36 of the buttons 28 and 29, respectively. This lever is provided with a depending arm or finger 37, in whose path of movement is interposed the double bevelled or wedge-shaped end or head of an up-

wardly spring pressed bolt or pin 38 suitably supported in a case 39. When the button 29 is depressed by the operator to its innermost position, the lever 33 is rocked in a 5 clockwise direction, in which movement the depending finger 37 depresses the pin 38 which will rise again after such finger has passed by its apex, such pin taking its position on the right hand side of the depending finger (Fig. 4) for the purpose of holding the buttons in their relative position, to which they have just been moved. The result of this movement of the buttons is to 10 open the circuit by removing the roller 32 from its co-operative relationship with the terminals. By preference, the buttons 28 and 29 which, as indicated in Fig. 4, have their bearings in the top of the extension 30 and also through the two lugs 40 and 41 therewithin, are arranged or disposed in a 15 plane parallel to the armature shaft and consequently to the line of thrust which is directly along the central axis of the tool or machine and through the axis of the tool 20 spindle. The direction of movement of the movable elements of this switch, that is the buttons, is in the direction of the longitudinal axis of the machine or drill and transverse to the longitudinal axis of the handles, with the result that the switch may be 25 operated and the drill thereby controlled without disturbing the position thereof with relation to the work, which might otherwise result when the tool is held simply by the 30 grasping hands. Moreover, the buttons are arranged on either side of the handle so as 35 to be easily controlled by the operator.

Referring next to the force feed device, the same comprises, in the present instance, a 40 yoke or U-shaped frame 42, whose parallel members are screw-threaded on their outer edges and enter the interior of the main casing through the top thereof. The cross piece of this yoke extends diametrically 45 across the top of the machine or drill and is provided at a point coincident with the longitudinal axis or line of thrust of the machine or drill, with a centering point 43. For the purpose of operating the yoke and 50 thereby changing its position with relation to the main casing to bring about a force feed, we provide a pilot wheel 44 internally screw-threaded to engage the screw-threaded arms or members of the yoke 42, the yoke being 55 moved up or down, that is in or out with respect to the main casing accordingly as the wheel is moved in one direction or the other. For the purpose of maintaining the pilot 60 wheel in fixed position with respect to the longitudinal axis of the tool or machine, we provide a retaining ring or cap 45, which is secured in suitable manner to the upper surface of the end head 9, which projects above the top plane of the main casing proper, the 65 wheel operating between such ring or cap 45

and such top plane or edge of the main casing, as clearly indicated in Fig. 1. This construction not only provides an efficient and serviceable force feed device, but also serves as a grasping handle when the yoke is moved 70 outwardly sufficient to permit the hand of the operator to grasp the cross piece of the yoke, such grasping handle, or rather the so called grip, being advantageous, especially in reaming operations and where it is desirable 75 that the operator shall hold the tool by one of the regular handles and also by a grip which is in a different position or location than the other regular grasping handle of the machine.

As illustrated in Fig. 1, the machine or drill may be provided with two grasping handles, the handle 31 already described, and also the handle 46, through the latter of which the leading-in wires or cable 47 of the 80 motor circuit may be passed. As seen in Fig. 1, these wires connect with a fuse 48 which is arranged opposite one of the openings 49 in the outwardly flared portion of the main casing 1, with the result that the fuse may be 85 easily and conveniently removed and a new one substituted. These openings 49, however, are primarily air ports for the passage of air and the same co-operate with a fan device for forcing a circulation of air through 90 the casing and among the elements or members of the motor, that is to say, our motor is air cooled. As herein shown, the fan 50 is secured to the lower bearing 51 on the armature shaft 8. The openings 49 are for the entrance or exit of the air accordingly as the 95 blades of the fan are so positioned as to force or draw the air through the motor casing.

The gear casing is by preference partially 100 or wholly filled with a suitable lubricant, desirably a heavy oil or a so called compression grease, or the like, and for the purpose of introducing such lubricant within the gear casing, I provide one or more openings closed by screw plugs 52.

As hereinbefore suggested, the type of 105 gearing in which my invention may be embodied may partake of different forms, as illustrated in Figs. 6 and 7. Referring first to the modification of Fig. 6, the armature pinion is operatively connected, as heretofore, with revolving pinions, but, in the present instance, such pinions marked 52 directly engage or mesh with the rack 53, instead of 110 being operatively connected therewith, through pinions on their hubs, as in Fig. 1. In this modification, the retaining ring 24 is dispensed with and the upper friction ring 25 is clamped between the head or diaphragm 6 and the upper edge of the rack. 115 In other respects, the construction and mode of operation is substantially the same as the device illustrated in Fig. 1. Referring next to the second modification illustrated in Fig. 7, the armature pinion meshes with the two 120

125 130

revolving pinions 54, which engage a permanently fixed circular rack 55 secured in a socket on the lower edge of the diaphragm 6. These revolving pinions rotate freely on studs 56, secured in the yoke 57, whose hub is journaled on the upward extension 58 of the tool spindle. This hub is formed as a pinion 59 engaging the two revolving pinions 60 mounted on the studs 61 of the revolving yoke 62, which is directly fastened or keyed to the tool spindle. These revolving pinions 60 mesh with the circular rack 63, which is provided with the friction rings 64, arranged at the opposite edges thereof. The tension-applying ring 65 presses against the upper edge of the rack and is held theretoward by means of the spring pressed studs 66. These studs are arranged in a case 67 formed in the diaphragm or head 6, in which screws the nut 68, for the purpose of adjusting the tension of the spring 69 therewithin. This form of gearing, which may be considered a double planetary type, operates in the same manner so far as the result of preventing overloading is concerned.

The brush holder in the present instance is constructed as illustrated in Fig. 5, which provides a simple arrangement, although other forms of brush holders may be employed. The brush holder comprises essentially a plate 70 secured to the upper head or end plate of the casing and having an extension 71 provided with an opening to receive the brush 72, which is forced head on against the commutator 73 of the motor, with a yielding resistance by means of the two flat springs 74, whose ends are fastened in the posts 75 rising from the plate 70.

40 We claim:

1. In an electric drill, the combination, with an electric motor and a tool spindle, of a train of gearing between said motor and tool spindle, one of the members of the train being a rack normally stationary but arranged to rotate and thereby destroy the operating connections between the motor and tool spindle when the load on the latter reaches a predetermined amount.

50 2. In an electric drill, the combination, with an electric motor and a tool spindle, of planetary gearing forming the operating connection between the motor and spindle, one member of the train being arranged to become inoperative when the load reaches a predetermined amount.

60 3. In an electric drill, the combination, with an electric motor and a tool spindle, of planetary gearing forming the operating connection between the motor and spindle, and comprising a rack and pinions, said rack being normally stationary but arranged to rotate when the load on the tool spindle reaches a predetermined amount.

65 4. In an electric drill, the combination,

with an electric motor and a tool spindle, of planetary gearing forming the operating connection between the motor and spindle and comprising a rack and pinions, and a casing or support with which said rack has frictional resistance up to a predetermined amount to resist a predetermined load on the tool spindle.

5. In an electric drill, the combination, with an electric motor and a tool spindle, of planetary gearing forming the operating connection between the motor and spindle, and comprising a rack and pinions, a casing or support, and a friction ring between said rack and casing whereby said rack will resist a load on the tool spindle substantially equaling the frictional resistance with said ring.

6. In an electric drill, the combination, with an electric motor and a tool spindle, of planetary gearing forming the operating connection between the motor and spindle and comprising a curved rack and pinions, and means for clamping said rack to resist a predetermined load on the tool spindle.

7. In an electric drill, the combination, with an electric motor and a tool spindle, of planetary gearing forming the operating connection between the motor and spindle and comprising a rack and pinions, and means for imparting a predetermined frictional resistance to the rack to resist a predetermined load on the tool spindle.

8. In an electric drill, the combination, with an electric motor and a tool spindle, of train of gearing forming the operating connection between the motor and spindle, one of the members of the train being a rack, and means for imparting to the rack a resistance adjustable in degree.

9. In an electric drill, the combination, with an electric motor and a tool spindle, of planetary gearing forming the operating connection between the motor and spindle, one of the members of the train being a rack, and means for imparting thereto a frictional resistance adjustable in degree to resist any predetermined load on the tool spindle.

10. In an electric drill, the combination, with an electric motor and a tool spindle, of planetary gearing forming the operating connection between the motor and spindle and comprising a rack and pinions and springs imparting a frictional resistance to the rack.

11. In an electric drill, the combination, with an electric motor and a tool spindle, of planetary gearing forming the operating connection between the motor and spindle and comprising a rack and pinions, springs imparting a frictional resistance to the rack, and means for varying the tension of the springs.

12. In an electric drill, the combination, with an electric motor and a tool spindle, of

- planetary gearing forming the operating connection between the motor and spindle and comprising a rack and pinions, friction rings bearing against the rack and means for varying the friction of such rings. 5
13. In an electric drill, the combination, with an electric motor and a tool spindle, of planetary gearing forming the operating connection between the motor and spindle 10 and comprising a rack and pinions, and a series of spring-pressed studs exerting pressure against the rack to hold the same with a predetermined frictional resistance. 13
14. In an electric drill, the combination, with an electric motor and a tool spindle, of planetary gearing forming the operating connection between the motor and spindle and comprising a rack and pinions, a friction ring bearing against the rack and a 20 series of spring-pressed studs bearing against the ring to hold the rack with a predetermined frictional resistance. 14
15. In an electric drill, the combination, with an electric motor and a tool spindle, of planetary gearing forming the operating connection between the motor and spindle and comprising a rack and pinions, a friction ring bearing against the rack, a series of spring-pressed studs bearing against the 30 ring to hold the rack with a frictional resistance, and means for adjusting the degree of tension exerted by such studs. 15
16. In an electric drill, the combination, with an electric motor and a tool spindle, of planetary gearing forming the operating connection between the motor and spindle and comprising a rack and pinions, a casing or support having a socket to receive such rack, and means for holding said rack therein with an adjustable frictional resistance. 40 16
17. In an electric drill, the combination, with a casing and with the electric motor armature arranged therein, of a fan within the casing which is provided with openings 45 for the passage of air, and fuse arranged in the electric motor circuit and located adjacent one of said openings for ready inspection and replacement. 17
18. In an electric drill, the combination, with a casing and with the electric motor armature arranged therein, of a force feed device comprising a screw-threaded yoke, and a screw-threaded wheel or ring engaging 50 said yoke and bearing against the casing. 18
- 55 19. In an electric drill, the combination, with a casing and with the electric motor armature arranged therein, of a force feed device comprising a yoke whose parallel members are screw-threaded and enter the 60 casing, and a screw-threaded ring engaging said yoke and bearing against the casing. 19
20. In an electric drill, the combination, with a casing and with the electric motor armature arranged therein, of a force feed 65 device comprising a U-shaped frame whose parallel screw-threaded members enter the casing and whose cross-piece extends diametrically across the outer end of the casing, and a screw-threaded ring engaging said yoke and bearing against the casing. 70 20
21. In an electric drill, the combination, with a casing and with the electric motor armature arranged therein, of a force feed device comprising a yoke whose parallel members are screw-threaded and enter the 75 casing, said yoke having a centering point, and a screw-threaded ring or wheel engaging said yoke and bearing against the casing. 21
22. In an electric drill, the combination, with a casing and with the electric motor armature arranged therein, of a force feed device comprising a screw-threaded yoke, and a screw-threaded wheel engaging said yoke and rotatably mounted on the casing and having a fixed relation thereto with 85 respect to the longitudinal axis thereof. 22
23. In an electric drill, the combination, with the casing and the motor armature therein, of an electric switch for controlling said motor, and grasping handles connected 90 with the casing, said switch having contact parts within said casing and an actuating part on the outside thereof adjacent a handle and within reach of the operator's hand. 23
24. In an electric drill, the combination 95 with the casing and the motor armature therein, of grasping handles on the casing, an electric switch for controlling said motor, said switch comprising contact parts within said casing, a button for operating said 100 contact parts, and another button for restoring said parts to their normal condition, said buttons projecting through the casing to the outside thereof and adjacent one of the handles. 24
25. The combination with an electric drill, of grasping handles on the casing, a controlling switch therefor, said switch being mounted upon said drill, and comprising contact parts, a part adapted to be moved to 110 operate said contact parts, and a part adapted to be moved to restore said operating part to its normal position. 25
26. In an electric drill, the combination 115 with the casing, and the motor therein, of a handle on said casing, and a switch for controlling said motor, said switch being mounted on said casing, and having two actuating parts, one located on either side of said handle. 120 26
27. In an electric drill, the combination with the casing, and the motor therein, of a handle secured on said casing, and a switch for controlling said motor, said switch being mounted on said casing and having an operating button, and a restoring button, said buttons being arranged for movement in the direction of the longitudinal axis of the drill, and being located one on either side of said handle. 125 27

28. The combination with an electric drill, of a switch for controlling the same mounted upon said drill, said switch having an actuating part arranged for movement in the direction of the longitudinal axis of the motor, whereby the drill may be controlled without disturbing its position with relation to the work. moved in the direction of the longitudinal axis of said drill.
29. In an electric drill, the combination with the casing and the motor therein, of a handle secured to the outside of the casing, and an electric switch for controlling said motor, said switch having its contact parts within said casing, and its actuating part 10 or button projecting through the casing in proximity to said handle, said button being movable substantially in the direction of the line of thrust of the drill. 34. In an electric drill, the combination with a casing, and a motor therein, of two handles rigidly secured to the outside of said casing at diametrically opposite points, and an electric switch for controlling said motor, said switch comprising contact parts located within said casing, an actuating key or button coöperating with said contact parts, a restoring key or button, and a link connecting said buttons projecting through said casing in proximity to said handle and being so disposed with relation to the drill that their operating movement is in the direction of the longitudinal axis thereof. 75
30. In an electric drill, the combination with the casing and the motor therein, of a handle secured to the casing, and an electric switch for controlling said motor, said switch comprising contact parts within said casing and an actuating part outside of said casing 15 in proximity to said handle, said actuating part being so disposed as to require a movement transverse to the longitudinal axis of said handle to actuate the same. 35. In an electric drill, the combination with the casing and the motor therein, of an electric switch for controlling said motor, said switch comprising contact parts and an actuating part, said actuating part being located upon the outside of said casing and being so disposed as to require a movement 20 thereof in the direction of the longitudinal axis of the motor to operate the switch. 80
31. In an electric drill, the combination with the casing and the motor therein, of an electric switch for controlling said motor, said switch comprising contact parts and an actuating part, said actuating part being located upon the outside of said casing and being so disposed as to require a movement 25 thereof in the direction of the longitudinal axis of the motor to operate the switch. 85
32. In an electric drill, the combination with the casing, and the motor therein, of a handle secured to the outside of said casing, an electric switch for controlling the circuit of said motor, said switch being mounted on said casing and having two actuating parts arranged in proximity to said handle, said parts being movable substantially in the direction of the line of thrust of the drill, one of said actuating parts 30 operating to make the circuit and the other to break the circuit. 90
33. In an electric drill, the combination with the casing, and the motor therein, of a handle secured to the outside of said casing, an electric switch for controlling the circuit of said motor, contact parts for said switch within said casing, and actuating parts for said switch projecting through said casing in proximity to said handle, said actuating parts being disposed one on either 35 side of said handle and being arranged to be 95
36. In an electric drill, the combination with the casing and the motor therein, of a handle secured on said casing, and a switch for controlling said motor, said switch being mounted on said casing, and having an operating button, a restoring button, said buttons being movable in the direction of the line of thrust of the drill, and means for holding the buttons in one position or the other with a yielding pressure. 100
37. In an electric drill, the combination with the casing and the motor therein, of a handle secured on said casing, and a switch for controlling said motor, said switch being mounted on said casing, and having an operating button, a restoring button, a connecting rocking lever between the buttons having a projecting finger, and a spring-pressed pin coöperating with said finger to hold the lever and the buttons in one position or the other, said buttons being movable 105 in the direction of the line of thrust of the drill. 105
